UNITED STATES PATENT OFFICE.

CORNELIUS B. HARDMAN, OF COLUMBUS, OHIO.

SAFETY DEVICE FOR IGNITION MECHANISM.

Application filed October 26, 1922. Serial No. 596,949.

To all whom it may concern:

Be it known that I, CORNELIUS B. HARDMAN, a citizen of the United States, residing at Columbus, in the county of Franklin and State of Ohio, have invented certain new and useful Improvements in Safety Devices for Ignition Mechanism, of which the following is a specification.

The present invention is directed to improvements in safety devices for ignition mechanism, and has for its primary object to provide means to prevent breakage of the magneto controlling arm should the same become inaccurately aligned with the tripping arm.

A further object of the invention is to provide a device of this character wherein the tripping arm is equipped with a spring pressed roller capable of yieldably engaging the magneto controlling arm should the lower end of the same be impinged thereagainst during the oscillation thereof.

With these and other objects in view, as will appear as the description proceeds, the invention consists in the novel features of construction, combinations of elements and arrangements of parts, and hereinafter to be fully described and pointed out in the appended claims.

In the accompanying drawing:

Figure 1 is a side elevation of the device,

Figure 2 is an enlarged longitudinal sectional view through the tripping arm, and

Figure 3 is a detail side elevation of the tripping arm showing the roller thereof impinged against the lower end of the magneto controlling arm.

Referring to the drawing 1 designates the timing shaft which is rotated in the customary manner, said shaft having fixed thereon an eccentric 2, said shaft being suitably journaled in the engine base 3.

A bracket 4 is supported by the base 3, the arm 5 thereof serving to support a magneto 6, the oscillating armature shaft thereof having fixed thereto a controlling arm 8 of the conventional type. Also carried by the bracket 4 is a bearing 9 in which is mounted a vertical shaft 10, the lower end of which has engaged therein an adjustable bolt 11, the purpose of which will appear later.

The tripping arm 12 has its lower end pivotally connected to the upper end of the

shaft 10, by a pin 13, the upper end of said arm being provided with a longitudinal recess 14 in which is located a coil spring 15. This arm is provided with diametrically opposed longitudinal slots 16 in which is slidably mounted a roller 17, the same being held against accidental displacement by cotter pins 18 in the ends thereof. The spring 15 has its upper end engaged with the roller 17 and serves to hold the same yieldably engaged with the upper end walls of said slots, whereby the roller will be normally positioned to strike the arm 8 on alternate sides to rock the same as said arm is oscillated.

In order to oscillate the arm 12 a rod 19 is employed, the forward end of which has secured thereto a head 20, the furcations 21 thereof being pivotally connected intermediate the ends of the arm 12 by a pin 22. The rear end of the rod 19 is threaded in the extension 23 carried by the band 24 which surrounds the eccentric 2, and since the timing shaft 1 is controlled by the engine shaft 22 through the medium of the gears 26 and 27, the shaft 19 will be reciprocated as the eccentric is rotated, thereby oscillating the tripping arm 12 which in turn rocks the arm 8 of the magneto 6.

The bracket 4 carries a bearing 28 in which is rotatably mounted the stem 29 of the cam 30, said stem having fixed therein the forward end of a rod 31, and since this cam engages the bolt 11 it will be obvious that the rod 31 may be rotated to cause the cam to raise or lower the shaft 10, and thus the arm 12 to advance or retard the spark, as desired. Since the bolt 11 is adjustable, it is obvious that this bolt may be adjusted to compensate for wear.

Normally the arm 12 strikes the arm 8 near the lower end thereof, first on one side and then on the other to oscillate the same, but at times when the speed of the engine varies the arm 8 will assume the position as shown in Figure 3, and at which time the end thereof will be in such angular relation with respect to the arm 12 that the arm 8 will have its lower end impinged against the roller 17, and should the arm 12 then oscillate the arm will break due to the direct line of strain imparted thereto. This objection is eliminated by the presence of the spring 15 which will permit the roller

2
to yield and move downwardly in the slots 18, thereby releasing the arm 8 in an obvious manner.

What is claimed is:

5. 1. In combination with the timing shaft of an internal combustion engine, of a magneto controlling arm, a tripping arm having a yieldably supported member carried thereby for engaging the magneto arm to oscillate the same, and means for oscillating the tripping arm.
- 10 2. In combination with the timing shaft

of an internal combustion engine, of a magneto controlling arm, a tripping arm having a roller slidably and yieldably carried thereby, said roller being adapted to alternately engage the opposite sides of the magneto arm to oscillate the same, said roller being capable of sliding downwardly relative the tripping arm when the lower end of the magneto arm is impinged thereagainst, as and for the purpose set forth.

In testimony whereof I affix my signature.
CORNELIUS B. HARDMAN.
